ABSTRACT

A dead stop assembly includes a deceleration member which is attachable at one end to a rail such that when a target retriever applies force to the deceleration member, the target retriever is decelerated. The deceleration member may be disposed in a housing which further engages the rail when the housing is impacted by a target retriever.

DEAD STOP ASSEMBLY

BACKGROUND

State of the Art

The present invention relates to a method for decelerating a target retriever. In particular, the present invention relates to a dead stop assembly which provides improved stopping of a target retriever.

FIELD OF ART

In order to properly train law enforcement officers and the military, it is important to train under live fire scenarios which help condition the trainee to respond appropriately to a given set of circumstances. In many cases this involves the trainee shooting at targets on a shooting range. For example, a target may be advanced a certain distance, e.g. 25 feet, and then turned to expose the target. In one scenario the target may include a photograph of an armed person pointing a gun at the officer, soldier, etc. In another scenario the target may be a photograph of a person holding out a cell phone or other device which does not pose a threat to the trainee. In still other scenarios a photograph may be placed on the target in which an armed person is holding a weapon and standing behind a hostage. By repeating such scenarios the trainee is taught to make split-second decisions regarding the need to fire or not. As the officer, soldier, etc. becomes more comfortable with his or her ability to rapidly assess and respond to different scenarios, the risk of fatality to the trainee and innocent bystanders is reduced.

In order to facilitate such training, many shooting ranges will have targets mounted on target retrievers. The target retrievers typically move along a rail. In some situations the retriever simply advances to a desired position, stops, and turns the target so as to expose the trainee to the desired scenario. In other situations, the target retriever may be moved at a high rate of speed. For example, a target may be turned at 25 feet from the trainee and then rapidly advanced toward the trainee to simulate an officer being attacked by a criminal. The officer may need to shoot three rounds within a desired area prior to the target being stopped.

Likewise, the target retriever may be alternately advanced towards and moved away from the trainee to simulate other scenarios. When done at a high rate of speed, the target retriever may have substantial inertia and may be difficult to stop. If the braking mechanism on the retriever is inadequate or fails, there is a need for a dead stop to prevent the target retriever from running off the rail and potentially injuring people. Because of the mass of a target retriever, they have been known to shear the bolts of a dead stop and create a potentially dangerous situation for the trainee or others in the area. Thus, it is desirable to provide a dead stop assembly which is robust and brings the target retriever to a more gradual stop.

SUMMARY OF THE INVENTION

The following summary of the present invention is not intended to describe each illustrated embodiment or every possible implementation of the invention, but rather to give illustrative examples of application of principles of the invention.

In some configurations, the invention may comprise a dead stop assembly for decelerating a target retriever. The

2

dead stop assembly may include a housing and a deceleration member for decelerating a target retriever.

In accordance with one aspect of the invention, the housing may include one or more projections for insertion into one or more slots disposed along a rail used to carry the target retriever.

In accordance with another aspect of the invention, the deceleration member may be attached at one end to the rail and attached in the opposing end to the housing.

In accordance with another aspect of the invention, the deceleration member may be a piston and cylinder which has a first extended position and a second, compressed position.

In accordance with another aspect of the invention, the deceleration member may be a spring which has a first, extended position and a second, compressed position.

In accordance with another aspect of the invention, the deceleration member may be rubber or foam which has a first, extended ambient condition and a second, compressed position.

In accordance with another aspect of the invention, the deceleration member may be formed from rubber or other elastic material which has a first, ambient position and a second, extended position for decelerating the retriever.

In accordance with another aspect of the invention, a position indicator may be disposed on the housing so as to provide a viewer with the ability to determine when the housing has been displaced due to impact with a target retriever.

It will be appreciated that aforementioned aspects of the invention are unique and that the invention can be implemented without all aspects set forth above. Therefore, no claim contained herein should be read as including any particular aspect without language setting forth such an element.

BRIEF DESCRIPTION OF THE DRAWINGS

40 Various embodiments of the present disclosure are shown and described in reference to the numbered drawings wherein:

45 FIG. 1 shows a target retriever system in accordance with the prior art;

FIG. 2 illustrates a rear elevated perspective view of a dead stop assembly disposed on a rail in accordance with one aspect of the present invention;

FIG. 3 illustrates an elevated perspective view of the dead stop assembly of FIG. 1 taken from the opposing side of the rail;

FIG. 4 illustrates a front elevated perspective view of the dead stop assembly of FIG. 1;

FIG. 5 illustrates a front elevated perspective view of the dead stop assembly taken from an opposing side of the rail;

FIG. 6 shows a front end view of the dead stop assembly disposed on the rail;

FIG. 7 shows a rear end view of the dead stop assembly disposed on the rail;

FIG. 8 shows a side view of the dead stop assembly disposed on the rail in a first, extended position;

FIG. 9 shows the opposing side view of the dead stop assembly on the rail in the first, extended position;

FIG. 10 shows a side view of the dead stop assembly on the rail in a second, retracted position;

FIG. 11 shows a top view of the dead stop assembly on the rail in the first, extended position;

FIG. 12 shows a side cross-sectional view of the housing of the dead stop assembly disposed on the rail in the first, extended position;

FIG. 13 shows a side cross-sectional view of the housing of the dead stop assembly disposed on the rail in the second, retracted position;

FIG. 14 shows an elevated perspective, exploded view of the dead stop assembly and rail; and

FIG. 15 shows a lower perspective, exploded view of the dead stop rail.

FIG. 16 shows a side view of another application of a dead stop assembly disposed in a first, extended position;

FIG. 17 shows a side view of the dead stop assembly in a second, compressed position;

FIG. 18 shows an exploded view of the dead stop assembly of FIGS. 16 and 17.

FIG. 19 shows a side cross-sectional view of a dead stop assembly using a spring;

FIG. 20 shows a side cross-sectional view of a dead stop assembly using a rubber or rubber-like material between an ambient state and a compressed state; and

FIG. 21 shows a side cross-sectional view of a dead stop assembly using rubber or a rubber-like material between an ambient state and an extended state.

It will be appreciated that the drawings are illustrative and not limiting of the scope of the invention which is defined by the appended claims. The embodiments shown accomplish various aspects and objects of the invention. It will be appreciated that it is not possible to clearly show each element and aspect of the present disclosure in a single figure, and as such, multiple figures are presented to separately illustrate the various details of different aspects of the invention in greater clarity. Similarly, not all configurations or embodiments described herein or covered by the appended claims will include all of the aspects of the present disclosure as discussed above.

DETAILED DESCRIPTION

Various aspects of the invention and accompanying drawings will now be discussed in reference to the numerals provided therein so as to enable one skilled in the art to practice the present invention. The skilled artisan will understand, however, that the methods described below can be practiced without employing these specific details, or that they can be used for purposes other than those described herein. Indeed, they can be modified and can be used in conjunction with products and techniques known to those of skill in the art in light of the present disclosure. The drawings and the descriptions thereof are intended to be exemplary of various aspects of the invention and are not intended to narrow the scope of the appended claims. Furthermore, it will be appreciated that the drawings may show aspects of the invention in isolation and the elements in one figure may be used in conjunction with elements shown in other figures.

Reference in the specification to "one embodiment," "one configuration," "an embodiment," or "a configuration" means that a particular feature, structure, or characteristic described in connection with the embodiment may be included in at least one embodiment, etc. The appearances of the phrase "in one embodiment" in various places may not necessarily limit the inclusion of a particular element of the invention to a single embodiment, rather the element may be included in other or all embodiments discussed herein.

Furthermore, the described features, structures, or characteristics of embodiments of the present disclosure may be

combined in any suitable manner in one or more embodiments. In the following description, numerous specific details may be provided, such as examples of products or manufacturing techniques that may be used, to provide a thorough understanding of embodiments of the invention. One skilled in the relevant art will recognize, however, that embodiments discussed in the disclosure may be practiced without one or more of the specific details, or with other methods, components, materials, and so forth. In other instances, well-known structures, materials, or operations may not be shown or described in detail to avoid obscuring aspects of the invention.

Before the present invention is disclosed and described in detail, it should be understood that the present invention is not limited to any particular structures, process steps, or materials discussed or disclosed herein, but is extended to include equivalents thereof as would be recognized by those of ordinary skill in the relevant art. More specifically, the invention is defined by the terms set forth in the claims. It should also be understood that terminology contained herein is used for the purpose of describing particular aspects of the invention only and is not intended to limit the invention to the aspects or embodiments shown unless expressly indicated as such. Likewise, the discussion of any particular aspect of the invention is not to be understood as a requirement that such aspect is required to be present apart from an express inclusion of that aspect in the claims.

It should also be noted that, as used in this specification and the appended claims, singular forms such as "a," "an," and "the" may include the plural unless the context clearly dictates otherwise. Thus, for example, reference to "a bracket" may include an embodiment having one or more of such brackets, and reference to "the target plate" may include reference to one or more of such target plates.

As used herein, the term "substantially" refers to the complete or nearly complete extent or degree of an action, characteristic, property, state, structure, item, or result to function as indicated. For example, an object that is "substantially" enclosed would mean that the object is either completely enclosed or nearly completely enclosed. The exact allowable degree of deviation from absolute completeness may in some cases depend on the specific context, such that enclosing the nearly all of the length of a lumen would be substantially enclosed, even if the distal end of the structure enclosing the lumen had a slit or channel formed along a portion thereof. The use of "substantially" is equally applicable when used in a negative connotation to refer to the complete or near complete lack of an action, characteristic, property, state, structure, item, or result. For example, structure which is "substantially free of" a bottom would either completely lack a bottom or so nearly completely lack a bottom that the effect would be effectively the same as if it lacked a bottom.

As used herein, the term "generally" refers to something that has characteristics of a quality without being exactly that quality. For example, a structure said to be generally vertical would be at least as vertical as horizontal, i.e. would extend 45 degrees or greater from horizontal. Likewise, something said to be generally circular may be rounded like an oval but need not have a consistent diameter in every direction.

As used herein, the term "about" is used to provide flexibility to a numerical range endpoint by providing that a given value may be "a little above" or "a little below" the endpoint while still accomplishing the function associated with the range.

As used herein, a plurality of items, structural elements, compositional elements, and/or materials may be presented in a common list for convenience. However, these lists should be construed as though each member of the list is individually identified as a separate and unique member.

Concentrations, amounts, proportions and other numerical data may be expressed or presented herein in a range format. It is to be understood that such a range format is used merely for convenience and brevity and thus should be interpreted flexibly to include not only the numerical values explicitly recited as the limits of the range, but also to include all the individual numerical values or sub-ranges encompassed within that range as if each numerical value and sub-range is explicitly recited. As an illustration, a numerical range of "about 1 to about 5" should be interpreted to include not only the explicitly recited values of about 1 to about 5, but also include individual values and sub-ranges within the indicated range. Thus, included in this numerical range are individual values such as 2, 3, and 4 and sub-ranges such as from 1-3, from 2-4, and from 3-5, etc., as well as 1, 2, 3, 4, and 5, individually. This same principle applies to ranges reciting only one numerical value as a minimum or a maximum. Furthermore, such an interpretation should apply regardless of the breadth of the range or the characteristics being described.

Turning now to FIG. 1, there is shown a target retriever system, generally indicated at 2, made in accordance with the prior art. The target retriever system 2 includes a target retriever 4 which typically includes an actuator 5 for turning a target 6. The target retriever 4 moves back and forth along the rail 7 under power of a motor unit 8. The target retriever 4 may be connected to the motor unit 8 by a cable or other connector. Alternatively, the target retriever 4 may include a motor unit contained within the retriever.

One concern with target retriever 4 is that the cable may get out of alignment or the braking mechanism may fail, thereby resulting in a retriever which will not stop at the appropriate location. To prevent risk of injury and potential damage to the target retriever 4, dead stops 9 are placed adjacent opposing ends of the rail 7 to provide emergency stopping for the target retriever. The dead stops 9, however, can potentially damage the retriever and may be sheared off if the retriever is traveling at a rate of speed which is too high.

Turning now to FIG. 2, there is shown an elevated perspective view of a dead stop assembly, generally indicated at 14, disposed on a rail 18. The rail 18 can be formed from a variety of materials and may have a variety of configurations. For example, rail 18 includes a first generally C-shaped member 18a and a second generally C-shaped member 18b placed back to back so as to form a structure similar to an I-beam with a channel 20 on the top and bottom. The generally C-shaped members may be attached in a variety of ways, including welding, adhesives and/or, as shown in FIG. 1, by the use of nuts and bolts 22.

The rail 18 may include one or more slots 26 to receive one or more projections 30 from the dead stop assembly 14. The projections 30 and channels 26 can be used to help the dead stop assembly move linearly when impacted by a target retriever (not shown). Moreover, the dead stop assembly 14 can be disposed in the channel 20 on either the upper side or lower side of the rail 18. (It will be appreciated that a dead stop assembly 14 disposed on the bottom of the rail 8 would typically include a structure for holding the housing of the dead stop assembly to the rail. This could be accomplished, for example, by a plurality of tabs which extend around the lower arm or cross-member 18c of the rail. However, in most

situations the dead stop assembly 14 will be disposed on top of the rail 18 to protect it from being hit by bullets and the like.)

The dead stop assembly 14 may include a housing 34 which may be configured to move within the channel 20 on the rail 18. The housing 34 may include a bracket 38 onto which the projections 30 may be mounted by nuts and bolts 42. This allows the projections 32 to be readily replaceable. Because the projections 32 extend below the upper cross-member of the rail 18, they are subject to being hit by bullets and, therefore, can be damaged. It will be appreciated, however, that the projections could be formed integrally with the housing 34 or the bracket 38.

As shown in FIG. 2, the housing has a first end 34a and a second end 34b. The first end 34a may be pointed and may be covered with a guard 46 made from steel or another ballistic grade material. The guard 46 is pointed so as to deflect bullets away from the housing in the event of an errant shot, while simultaneously minimizing ricochets back towards the shooter. Thus, it will be appreciated that the dead stop assembly 14 shown in FIG. 2, may be positioned at the distal end (i.e., the end opposite the shooter) of the rail 18. A similar dead stop assembly 14 may also be placed at the proximal end of the rail 18. In such a configuration, the pointed first end 34a would be pointing away from the shooter and toward the distal end.

Also shown in FIG. 2 is a hanger 50 which is used to suspend the rail 18 from the ceiling. The hanger 50 may include a gripping bracket or gripping member 54 which extends under the upper arms or cross-members 18f of the rail 18. A support rod or cable 58 may be attached to the gripping member 54 and extend upwardly to a ceiling or other suspension member. It will be appreciated that the gripping member 54 is preferably shaped so as to not interfere with the movement of the dead stop assembly 14.

FIG. 3 shows the dead stop assembly 14 and rail 18 from the opposite side, so that the opposing channel and opposing projection 30 are visible. FIG. 3 is thus numbered according to the description of FIG. 2.

FIG. 4 shows an elevated front view of the rail 18 and the dead stop assembly 14. The guard 46 at the front end 34a of the housing 34 is shown. If a bullet is fired toward the front end 34a of the housing 34, the bullet will be deflected away from the housing but still downstream so it may be collected by the bullet trap, etc., past the distal end of the rail. FIG. 5 shows a similar view from the opposing side of the rail 18, and FIGS. 4 and 5 are numbered in accordance with the description given as to FIG. 2.

Turning now to FIG. 6 there is shown a front end view of the rail 18. The housing 34 of the dead stop assembly 14 is not visible because it is concealed by the guard 46. The view also shows the gripping member 54 extending around the upper arm or cross-members 18f of the rail. A pair of bolts 62 may be used to engage an upper flange 18d of the rail 18 so that the rail is properly held in place by the gripping member 54. The bolts 62 are preferably positioned so that they do not interfere with movement of the dead stop assembly 14. The bolts and washers 66 disposed along the rod or cable 58 can be used for attachment to a support wire. Alternatively, they may be used to help hold a baffle above the rail 18 for deflecting bullets.

Also visible in FIG. 6 are the front faces 30a of the projections 30 which are extending downwardly through the slots (not visible in FIG. 6) in the upper cross-members 18f of the rail 18. The front faces 30 may be configured to

engage the rail at one end of the slot so as to stop forward movement of the dead stop assembly 14 when it returns to its first, extended position.

FIG. 7 shows a rear view of the housing 34, the bracket 38 and the projections 30. Also visible are the rear faces 30b of the projections 30 extending through the rail 18. Furthermore the gripping member 54 along with the bolt 62 and the rod or cable 58 are shown as well. FIGS. 6 and 7 also show an attachment nut 68 which secures the gripping member 54 adjacent the end 70 of the rod or cable 58 in the gripping member.

Turning now to FIG. 8, there is shown a side view of the dead stop assembly 14 disposed on top of the rail 18 in a first, extended position. In the first extended position, the projections 30 are disposed adjacent a proximal end of the slots 26 when on a distal end of the rail 18 and adjacent a distal end of the slots when on a proximal end of the rail. Also shown in FIG. 8 is the gripping member 54, the rod or cable 58 and the bolt 62. FIG. 9 can represent either an opposing side view on the other side of the rail, or the position of the dead stop assembly at the opposing end of the rail. In FIG. 9, the dead stop assembly 14 is in a first, extended or ambient state is numbered in accordance with the previous figures.

FIG. 10 shows a view similar to that shown in FIG. 9, except that the dead stop assembly 14 has been pushed from the first, extended position into a second retracted position. This is shown by the position of the projections 30 within the slot 26. The front face 30a of the projection 30 has been moved rearwardly away from the end 26a of the slot 26. If the view shown in FIG. 10 was of the distal end of the rail 18, end 26a of the slot 14 would be the proximal (i.e. shooter) end of the slot, such that the dead stop assembly 14 has been pushed distally so that the projections 30 are closer to the distal ends 26b of the slots. Alternatively, if the image shown were of the proximal end of the rail 18, the end 26a of the slot 26 would be the distal end, with the dead stop assembly having been pushed by impact from the target retriever represented by dashed lines 72. In such a position the rear face 30b of the projections 30 are disposed adjacent the opposing end 26b of the slot 26.

FIG. 11 shows a top view of the dead stop assembly 14 disposed on the rail 18 with the slots 26 being readily visible. Also shown in FIG. 11 is top view of the gripping member 54 which engages and holds the rail 18 in place. The other portions of the dead stop assembly 14 and the rail 18 are discussed previously and are numbered accordingly in FIG. 11.

Turning now to FIG. 12, there is shown a cross-sectional view of the dead stop assembly 14 when the dead stop assembly is in a first, extended position. Disposed inside the housing 34 is a deceleration or dampening member 76, which may be a spring, a shock absorber, a pneumatic spring 78 (shown in FIG. 12) or other mechanism. A first end 76a is attached to the housing 34 of the dead stop assembly 14 by an attachment member. This may include, for example, bolting the first end 76a to an attachment member, such as tab 80, which may be attached the housing 34 or to the guard 46. (It will be appreciated that the tab 80 may be welded to the housing or the guard. Additionally, it will be appreciated that the attachment may be made so as to allow the deceleration member 76 to pivot with respect to the tab.)

The opposing second end 76b may be attached to a tab 84 which is attached via a bracket 88 to the rail 18. Unlike the first end 76a, the second end 76b of the deceleration member 76 will generally not move linearly when the guard 46 is struck by a target retriever. Thus, the dampening member 76

will be moved into a second, compressed orientation such as that shown in FIG. 13. This corresponds with a movement of the housing 34 toward the end of the rail 18. As the deceleration member 76 compresses into the second position, it will decelerate the target retriever and bring it to a substantial stop. The deceleration member 76 will then move back into the first, extended orientation shown in FIG. 12 and will move the housing 34 and the target retriever back.

Because the dead stop assembly 14 decelerates the target retriever to a stop over a distance of, for example, 6 to 8 inches instead of immediately, less harm is potentially done to any sensors or other instruments carried by the target retriever. Additionally, the risk that the target retriever will simply break off the dead stop is substantially reduced as well. Therefore, the dead stop assembly 14 may provide for a longer functional life, as well as doing less damage to a target retriever that has not been properly braked.

Turning now to FIG. 14, there is shown an elevated, perspective exploded view of the dead stop assembly 14, the rail 18 and other parts. At the top, the housing 34 is shown with the guard 46 on one end and the bracket 38 with the projections 30 at the other end. Disposed below the housing 34 is a pin or bolt 90 which connects the end 76a of the deceleration member 76 to the housing 34. Also shown is a second pin or bolt 92, which can be used to attach the second end 76b of the deceleration member 76 to the tab 84. The pin or bolts 90, 92 may also include a retainer 98 for engaging one of the nuts to help hold the pins in place.

The tab 84 may be formed integrally with or otherwise attached to the bracket 88. The bracket 88 may include a plurality of holes 94 which may be disposed in alignment with holes 18e in the rail 18 so that nuts and bolts 96 can be used to anchor the bracket 88 in place on the rail. Also visible in the rail 18 are the slots 26 in which the projections 30 slide as the housing 34 moves back and forth after being impacted by a target retriever.

FIG. 15 shows a lower perspective, exploded view similar to that shown in FIG. 14 and the various components are numbered accordingly. It will be appreciated that alternative means could be used for securing the bracket 88 to the rail 18 and/or the deceleration mechanism 76 to either the tab 84 or the tab 80 of the housing. Posts, pins, bolts and other fasteners may be used.

Turning now to FIG. 16, there is shown a side view of another application of a dead stop assembly 14 disposed in a first, extended position. The dead stop assembly 14 does not ride in the channel 20 (see FIG. 18) formed by the upper arms or crossmembers and flange 18d. Rather, the dead stop assembly 14 may be disposed on the center wall of the rail 18. The dead stop assembly 14 may include a housing 34 having a first end 34a and a second end 34b. Disposed at the first end 34a may be a guard 46. Rather than being beveled as the guard shown in the previous drawings, the guard 46 in FIG. 16 is sloped at a downward angle so as to deflect bullets downwardly should guard be struck. The guard 46 may also include an engagement member 46a which is designed to engage a target retriever 72 when the target retriever is unable to stop properly.

As will be explained in additional detail later, the guard 46 may be attached to the housing 34 by one or more pin or bolt 90, or other fastener. The housing 34 may move along a slot or channel 26 formed in the rail 18. As shown in FIG. 16, the guard 46 is disposed at a first end of the channel 26. FIG. 17 shows the dead stop assembly 14 after the guard 46 has been impacted by a runaway target retriever represented by dashed lines 72. The entire housing 34 has been moved to the right, which would be distally if the dead stop assembly

14 were on the far end of the rail 18, or proximally if the dead stop assembly were on near a proximal end of the rail. The movement of the housing 34 reveals more of the slot or channel 26. While FIG. 17 shows the housing 34 extending beyond the end of the rail, the dead stop assembly 14 could be positioned so that housing member never extended beyond the end of the rail 18.

Turning now to FIG. 18, there is shown an exploded view of the dead stop assembly 14 of FIGS. 16 and 17. The dead stop assembly 14 includes the housing 34 which may have a slot 34c formed therein. Normally disposed inside the housing 34 is a damping or deceleration member 76 which has a first end 76a which may attach to a tab 80 on the guard 46 via a pin, bolt or other fastener. The damping or deceleration member 76 may also have a second end 76b which attaches to rail 18 via a pin, bolt or other fastener. When the guard 46 is impacted by the target retriever 72, the damping or deceleration member 76 acts as an air spring and decelerates the target retriever over a distance that reduces the risk of damage to the target retriever and lessens the risk of the target retriever shearing off the dead stop assembly.

FIG. 19 shows a side cross-sectional view of a dead stop assembly 14 wherein the damping or deceleration mechanism 76 is a spring 78. When a target retriever (not shown) forcibly impacts the dead stop assembly, the spring 78 compresses as the housing 34 moves so as to more gradually slow down the target retriever. The spring 78 may have ends 76a and 76b which are attached to brackets 80 and 88 similar to the damping or deceleration mechanisms discussed above, or may simply have a spring contained within a chamber such that movement of the housing 34 is resisted by compression of the spring. The remaining structures of the dead stop assembly 14 and the rail 18, etc., may be similar to those described above and are numbered accordingly. However, it will be appreciated that the spring 78 and the dead stop assembly 14 need not be connected to the rail 18 in the same manner as discussed above.

FIG. 20 shows a side cross-sectional view of a dead stop assembly 14 using a rubber or rubber-like material, such as a resilient compressible foam or other resilient material to act as the deceleration member 76. The material may simply be held in the housing 34 in such a way that movement of the housing compresses the material. Alternatively, the material forming the deceleration member 76 may have ends 76a and 76b which attach to brackets on the housing 34 or guard 46 and to the rail 18. The dead stop 14 may convert the energy of the runaway target retriever into the force necessary to temporarily compress the material forming the deceleration member 76. Once the target retriever has been stopped, the deceleration member 76 may return to its original position and be ready for the next impact with the target retriever.

FIG. 21 shows a side view of a dead stop assembly 14 using rubber or a rubber-like material between an ambient state and an extended state. The dead stop assembly 14 may include a housing 34. A front end 34a of the housing 34 may be attached to a guard 46. The guard 46 may have an angled surface to help deflect any bullets which may impact the guard. The opposing end 34b of the housing 34 may include a bumper 36 to cushion any impact between the housing and the middle wall of the rail 18.

The housing 34 may be attached to a damping or deceleration mechanism 76 to decelerate the housing and thus a target retriever which forcefully impacts the housing. The housing 34 may be attached by a post 81 or other attachment to a resilient band or other form of spring. The opposing end of the resilient band or spring 78 may be attached by a post

79 or other attachment to the rail 18. When a target retriever impacts the guard, the housing 34 moves toward the opposing end of the channel 26 in the rail 18. As it does so, the resilient band or spring 78 stretches, but resists movement of the housing 34, thereby decelerating the housing and the target retriever. If the resilient band or spring 78 is not sufficient to stop the housing 34 before it impacts the opposing end of the channel, the bumper 36 will help to reduce the force of the impact as it engages the rail. Thus, the target retriever will be slowed, both reducing the risk of damage to the target retriever and substantially reducing the risk that a high velocity target retriever will simply shear off the dead stop. Both help to prevent damage, reduce repair costs and promote longevity of the system.

It will be appreciated that the disclosure herein includes various parts and assemblies which can be used together. Thus, the present disclosure teaches a dead stop assembly for decelerating a target retriever moving along a rail, the dead stop assembly may include a deceleration member having a first end and a second end, and wherein the deceleration member is movable between a first, extended orientation and a second, compressed orientation and where in the first end is movable with respect to the rail and the second end is attached to the rail. Further more the dead stop assembly may include a second end of the deceleration member attached to the rail by a bracket; a second end of the deceleration member is pivotably attached to a bracket; a bracket including a tab extending upwardly away from the rail; a first end of the deceleration member being attached to the housing, or combinations thereof.

The dead stop assembly may include a deceleration member disposed inside the housing, and a tab disposed inside the housing, the first end of the deceleration member being attached to the tab; a guard disposed at one end of the housing, the guard being generally pointed and made from a ballistic material; a tab attached to the guard; at least one projection extending from the housing; a rail having at least one slot and wherein the projection extends into the slot; at least one projection attached to the housing by a bracket; and/or a projection is attached to the bracket by a plurality of removable fasteners, and combinations thereof.

The rail may include a topside and a plurality of slots and holes disposed in the topside; and the plurality of slots may extend generally lengthwise along the rail.

A dead stop assembly may include a bracket configured for attachment to a rail, a deceleration member having a first end and a second end, the second end being configured for attachment to the bracket and a housing, the housing having an attachment member for attachment to the first end of the deceleration member and at least one projection extending from the housing. The dead stop assembly may also include: at least one projection is attached to the housing by a removable fastener; first end of the deceleration member which is pivotably attached to the housing and wherein the second end of the deceleration member is pivotably attached to the bracket; a first pin and a second pin for connecting the deceleration member to the bracket and to the housing, respectively; and/or at least one projection extending from the housing having a first projection and a second projection, the first projection and the second projection being removably attached to a bracket and the bracket being attached to the housing, or combinations thereof.

The present disclosure also teaches method for decelerating a target retriever moving along a rail, having a dead stop assembly including a deceleration member movable between a first, extended orientation, and a second, compressed orientation, wherein the deceleration member has a

11

first end and a second end and wherein the second end is attached to the rail so as to stop the second end from moving linearly when the deceleration member is impacted by a target retriever. The method may include attaching a housing to the first end of the deceleration member and having at least one projection attached to the housing member slide within a slot on the rail when the housing is impacted by a target retriever.

The present disclosure also teaches A dead stop assembly for stopping a target retriever moving along a rail, the dead stop assembly comprising a housing movable between a first position and a second position, the housing member having guard at one end for engaging the target retriever, a deceleration member attached to the housing and to the rail, the deceleration member disposed to slow movement of the housing from the first position to the second position, and wherein at least one of the dead stop assembly and the rail have a channel formed therein to facilitate sliding of the dead stop assembly.

Thus, there is disclosed a dead stop assembly and method of use. It will be appreciated that numerous modifications may be made without departing from the scope and spirit of this disclosure. The appended claims are intended to cover such modifications.

What is claimed is:

1. A dead stop assembly for decelerating a target retriever moving along a rail having a slot extending therethrough, the dead stop assembly comprising:

a housing; and

a deceleration member having a first end and a second end, the deceleration member being movable between a first, extended orientation and a second, compressed orientation and wherein the first end is movable with respect to the rail and the second end is attached to the rail, wherein the deceleration member is attached at the first end to the housing and wherein a portion of the dead stop assembly extends through the slot extending through the rail.

2. The dead stop assembly for decelerating a target retriever moving along a rail of claim 1, wherein the second end of the deceleration member is attached to the rail by a bracket mounted on the rail and wherein the housing slides along the rail as the deceleration member is moved from the first, extended orientation to the second, compressed orientation.

3. The dead stop assembly for decelerating a target retriever moving along a rail of claim 2, wherein the second end of the deceleration member is pivotably attached to the bracket.

4. The dead stop assembly for decelerating a target retriever moving along a rail of claim 2, wherein the bracket includes a tab extending upwardly away from the rail so that the tab is disposed above the rail and the second end of the deceleration member is disposed above the rail.

5. The dead stop assembly for decelerating a target retriever moving along the rail of claim 1, wherein the housing and the deceleration member are disposed on top of the rail and wherein the housing is slidable along the top of the rail as the deceleration member returns to the first, extended orientation.

6. The dead stop assembly for decelerating a target retriever moving along the rail of claim 5, wherein the deceleration member is disposed inside the housing, and wherein a tab is disposed inside the housing, the first end of the deceleration member being attached to the tab.

7. The dead stop assembly for decelerating a target retriever moving along the rail of claim 5, further comprising

12

ing a guard disposed at one end of the housing, the guard being generally pointed and made from a ballistic material.

8. The dead stop assembly for decelerating a target retriever moving along a rail of claim 7, further comprising a tab attached to the guard.

9. The dead stop assembly for decelerating a target retriever moving along a rail of claim 5, wherein the dead stop assembly includes at least one projection extending from the housing and through the slot extending through the rail.

10. The dead stop assembly for decelerating a target retriever moving along a rail of claim 9, wherein at least one projection extending from the housing is attached to the housing by a bracket.

11. The dead stop assembly for decelerating a target retriever moving along a rail of claim 10, wherein the projection is attached to the bracket by a plurality of removable fasteners.

12. The dead stop assembly for decelerating a target retriever moving along a rail of claim 1, wherein a portion of the housing extends through the slot.

13. The dead stop assembly for decelerating a target retriever moving along a rail of claim 1 wherein the rail has a topside and wherein the slot comprises a plurality of slots disposed in the topside and extending through the topside.

14. The dead stop assembly for decelerating a target retriever moving along a rail of claim 13, wherein the plurality of slots extend generally lengthwise along the rail.

15. A dead stop assembly for decelerating a target retriever along a rail having a slot extending therethrough, the dead stop assembly comprising a bracket configured for attachment to a rail, a deceleration member having a first end and a second end, the second end being configured for attachment to the bracket and a housing, the housing having an attachment member for attachment to the first end of the deceleration member and at least one projection extending from the housing and positioned extending through the slot so as to slide within the slot of the rail when the dead stop assembly is impacted by the target retriever.

16. The dead stop assembly of claim 15, wherein the at least one projection is attached to the housing by a removable fastener.

17. The dead stop assembly of claim 16, wherein the first end of the deceleration member is pivotably attached to the housing and wherein the second end of the deceleration member is pivotably attached to the bracket.

18. The dead stop assembly of claim 17 further comprising a first pin and a second pin for connecting the deceleration member to the bracket and to the housing, respectively.

19. The dead stop assembly of claim 15, wherein the at least one projection extending from the housing comprises a first projection and a second projection, the first projection and the second projection being removably attached to a bracket and the bracket being attached to the housing, the rail having a second slot such that the first projection extends through the first slot and the second projection extends through the second slot.

20. A method for decelerating a target retriever moving along a rail, the method comprising selecting a dead stop assembly including a housing, positioning a portion of the housing to extend through a slot in the rail, selecting a deceleration member having a first end and a second end, and attaching the second end to the rail so as to stop the second end from moving linearly when the deceleration member is impacted by a target retriever.

21. The method for decelerating a target retriever moving along the rail of claim 20 wherein the method further

comprises attaching the housing to the first end of the deceleration member and having at least one projection attached to the housing member slide within a slot extending through the rail when the housing is impacted by a target retriever.

5

22. A dead stop assembly for stopping a target retriever moving along a rail, the dead stop assembly comprising a housing movable between a first position and a second position, the housing member having guard at one end for engaging the target retriever, a deceleration member ¹⁰ attached to the housing and to the rail, the deceleration member disposed to slow movement of the housing from the first position to the second position, and wherein the rail has a channel formed therethrough to facilitate sliding of the dead stop assembly along the rail and wherein the housing ¹⁵ extends through the channel formed through the rail.
